[57] CLAIM

The ornamental design for a detachable container handle, as shown and described.

DESCRIPTION

FIG. 1 is a perspective view of the detachable container handle showing my new design, the container shown in broken lines;

FIG. 2 is a top plan view thereof;

FIG. 3 is a fragmentary bottom plan view thereof;

FIG. 4 is a right side elevational view thereof;

FIG. 5 is a fragmentary left side elevational view thereof;

FIG. 6 is a rear elevational view thereof; and,

FIG. 7 is a front elevational view thereof.
